[57] CLAIM

The ornamental design for a toaster product, substantially as shown and described.

DESCRIPTION

FIG. 1 is a plan view of a toaster product showing my new design;

FIG. 2 is an edge view;

FIG. 3 is a sectional view taken on line 3—3 of FIG. 2;

FIG. 4 is a plan showing a modified form of my new design;

FIG. 5 is an edge view;

FIG. 6 is a sectional view taken on the line 6—6 of FIG. 5;

FIG. 7 is a plan view of another modified form of my new design;

FIG. 8 is an edge view; and

FIG. 9 is a sectional view taken on the line 9—9 of FIG. 8.
